UNITED STATES PATENT OFFICE.

CLYDE J. COLEMAN, OF ROCKAWAY, NEW JERSEY, ASSIGNOR TO THE HALL SIGNAL COMPANY, A CORPORATION OF MAINE.

RAILWAY-TRAFFIC-CONTROLLING APPARATUS.

No. 858,793.

Specification of Letters Patent.

Patented July 2, 1907.

Application filed November 7, 1904. Serial No. 231,670.

To all whom it may concern:

Be it known that I, CLYDE J. COLEMAN, a citizen of the United States, residing at Rockaway, in the county of Morris and State of New Jersey, have invented certain new and useful Improvements in Railway-Traffic-Controlling Apparatus and Systems, of which the following is a specification, reference being had therein to the accompanying drawings, forming a part thereof.

My present invention relates to railway-traffic-controlling apparatus and systems such as railway signaling apparatus and systems, and, in various features, is of a nature supplementary to the invention disclosed by me in my application for Letters Patent of the United States filed on the 11th day of April, 1904, Serial No. 15 202,536.

In its embodiment which is illustrated in the accompanying drawings, and particularly described herein-after, my invention relates to an electrically controllable railway traffic-controlling apparatus and system, 20 which are in this instance, a railway signaling apparatus and system, comprising fluid-pressure motive apparatus for supplying actuating mechanical energy necessary to operate traffic-controlling or signaling means.

25 The illustrated embodiment of my invention is a normal clear traffic-controlling or signaling apparatus and system, that is to say, a traffic-controlling or signaling apparatus and system which are normally maintained in clear or non-blocking condition permitting the free passage of trains or railway vehicles past the traffic-controlling point or points at which traffic on the railway is controlled by the traffic-controlling or signaling apparatus.

30 The illustrated embodiment of my invention is a railway block signaling system in which the traffic-controlling or signaling apparatus at a given traffic-controlling or signaling point indicates, and is governed by, the condition of only one railway block, which is the railway block in advance of the given traffic-controlling or signaling point.

40 However, by the obvious application of well known methods and principles, my invention may be embodied in normal danger or normal blocking railway traffic-controlling or signaling apparatus and systems, 45 and also in home-and-distant railway traffic-controlling or signaling apparatus and systems in which the traffic-controlling or signaling apparatus at a given traffic-controlling or signaling point indicates, or is controlled by, the conditions of two railway blocks, for instance two 50 railway blocks successively in advance of the given traffic-controlling or signaling point as in the case of the ordinary home and distant railway signaling systems.

Broadly stated, the objects of my invention are reliability and economy of operation, simplicity, compact-

ness and economy of construction, and economy of maintenance.

These objects are attained by the various features of my invention which are fully disclosed in the following description and accompanying drawings, and which are particularly pointed out in the claims annexed hereto.

Subservient to the broad ends mentioned above, my invention comprises various objects capable of more particular definition, all of which will clearly appear in the light of the following description of the particular embodiment of my invention which I have illustrated. 65 I shall at this point mention various of these subservient objects, together with various features of my invention.

It is one object of my invention to provide a common source for supplying heat or thermal energy to two different thermal energy-transmuting apparatuses 70 employed in railway traffic-controlling or signaling apparatus for transmuting thermal energy into energy for actuating, or controlling the actuation of, the traffic-controlling or signaling means. To this end my invention comprises two thermal energy-transmuting means 75 or apparatuses arranged to deliver energy for actuating, or controlling the actuation of, the traffic-controlling or signaling means, such as a signal semaphore. For instance, the illustrated embodiment of my invention comprises fluid-pressure motive apparatus co-operative 80 with the traffic-controlling or signaling semaphore to actuate the same and so arranged that its motive fluid is heated by a source of heat which is also employed to supply thermal energy to a thermo-electric energy-transmuting device, which is shown in the drawings as 85 a thermopile and which supplies electric energy to a controlling electric circuit which controls the actuation of the traffic-controlling or signaling semaphore by the fluid-pressure motive means.

It is another object of my invention to economize 90 the thermal energy delivered by the source of heat such as mentioned above, and to this end my invention comprehends an arrangement of two thermal energy-transmuting apparatuses, each of which is arranged to deliver its transmuted energy for the actuation or control of 95 the traffic-controlling or signaling means, while one of the thermal energy-transmuters is arranged to receive and transmute the waste or surplus or non-utilized heat or thermal energy which the other thermal energy-transmuter fails to convert into useful energy. 100 For instance, in the illustrated embodiment of my invention a heating means is provided as a source of thermal energy for the thermo-electric energy-transmuter or thermopile, while the fluid-pressure motive apparatus is arranged to receive and utilize non-utilized heat which passes through, or by, or away from, the thermo-electric energy-transmuter or thermopile. 105

It is another object of my invention to utilize a

energy for traffic-controlling or signaling means, for instance as a source of energy for moving or assisting to move a signal semaphore, and to this end my invention comprehends a fluid-pressure motive chamber or expansion chamber in actuating co-operation with the traffic-controlling or signaling means, or signal-semaphore, and a source of motive fluid communicating with the motive chamber, and a source of heat arranged to heat the motive fluid, the fluid thus heated being utilized in the motive chamber to produce motive force and mechanical energy for actuating the traffic-controlling means such as the signal semaphore.

In its application to railway traffic-controlling apparatus and systems employing fluid-pressure motive apparatus comprising a source of motive fluid under pressure for actuating the traffic-controlling means, it is a further object of my invention to prevent the excessive cooling of the motive fluid and surrounding portions of the motive fluid apparatus, due to the dynamic expansion of the motive fluid as it is utilized to produce motive power. To this end, my invention comprises a means for heating those portions of the fluid-pressure motive apparatus which are subjected to a cooling tendency by contact with the expanded motive fluid. For instance, in the illustrated embodiment of my invention the motive chamber or cylinder and the motive fluid conduit leading thereto are arranged to be heated by a source of heat. In the present instance, for purposes of economy and compactness, this source of heat is also employed to supply thermal energy to a thermo-electric energy-transmuter or thermopile arranged to supply electrical energy for controlling the actuation of the traffic-controlling means.

The foregoing feature of my invention prevents excessive cooling of the motive fluid and motive fluid apparatus due to dynamic expansion of the motive fluid, and also prevents excessive cooling of the motive fluid apparatus due to expansion of the motive fluid escaping therefrom when an exhaust vent is opened, and this feature is particularly valuable in its application to those forms of fluid-pressure motive apparatus which employ, as a source of motive fluid, a liquefied gas such as liquid carbonic acid or carbon dioxid, which, by its volatilization and dynamic or other expansion, incurs very low temperatures.

In some instances wherein a controlling valve is employed to govern the passage of motive fluid to or from the motive chamber, as in that embodiment of my invention which is illustrated by the accompanying drawings, and when such valve comprises a rubber valve seat coming in contact with the motive fluid flowing to the motive chamber, or when for any other reason it is desired to keep the controlling valve cool, another object of my invention is to maintain such a valve in relatively cool condition and thus prevent any undesirable effect of heat thereon, such as injury to the valve proper or seat, or other deterioration of the valve which might be caused by the passage of heated motive fluid if the same were heated prior to its passage through the controlling valve, and to this end my invention comprises an arrangement of the motive fluid apparatus and a source of heat, whereby the motive

fluid is only heated after its passage through the controlling valve.

The foregoing preamble does not essay to enumerate and separately mention each and every distinct object and feature of my present invention, since all such objects and features will be clearly apparent in the light of the following particular description of my invention in that particular embodiment which is illustrated in the accompanying drawings.

In these drawings: Figure 1 is a diagram illustrating railway traffic-controlling or signaling apparatus embodying my invention and adapted for location, and for controlling traffic, at a traffic-controlling point upon a railway line. Fig. 2 is a diagram illustrating two traffic-controlling or signaling apparatuses, such as the apparatus of Fig. 1, but co-organized in their control of railway traffic at two successive traffic-controlling points along a common railway line.

My invention may be embodied in traffic-controlling or signaling apparatus employing fluid pressure motive apparatus for actuating the traffic-controlling or signaling means, such as the signal semaphore 2, and employing a source of liquefied gas such as the tank 51, which may contain liquid carbonic acid or carbon dioxid.

In the illustrated embodiment of my invention the source of liquefied gas communicates with an expansion reservoir 43 through a connecting pipe 50, reducing valve 45, and connecting pipe 44. It is the function of the reducing valve 45 to expand the motive fluid or gas and reduce its pressure as it is fed through such reducing valve from the tank 51 to the expansion reservoir 43. A double gage, such as the one illustrated, may be connected to the reducing valve so as to indicate simultaneously the pressures in the liquid tank 51 and in the expansion reservoir 43. In this instance, the index hand 47 indicates upon its scale 49 the fluid pressure in the liquid tank, while the index hand 46 indicates on its respective scale 48 the fluid pressure in the expansion reservoir 43. The expansion reservoir communicates through a connecting pipe 42 with the pressure chamber 35 of the casing 34 of the controlling valves. This casing comprises three chambers, the pressure chamber 35, which has already been mentioned and which occupies one end of the valve casing 34, the intermediate chamber 36, and the discharge chamber 37 occupying that end of the valve casing opposite its pressure chamber. The discharge chamber is open at its lower end to the atmosphere. An inlet valve seat is interposed between the pressure chamber and the intermediate chamber, and an outlet valve seat is interposed between the intermediate chamber and the discharge chamber, and an inlet valve 40 and an outlet valve 38 co-operate with the valve seats and are mounted upon a common valve stem 39, so that when the valve stem is thrust longitudinally in one direction, for instance by gravitation as in the present instance, the inlet valve 40 will engage its seat and close communication between the pressure chamber 35 and the intermediate chamber 36, while the outlet valve 38 will recede from its seat and open communication between such intermediate chamber 36 and the discharge chamber 37 so as to permit discharge of motive fluid from the intermediate

100

115
120
125

chamber through the discharge chamber to the outer atmosphere. The resulting position of the valves is shown in Fig. 1. When the valve stem is thrust longitudinally in its opposite direction, the outlet valve 5 will be closed and the inlet valve will be opened. In the construction shown the valves will be normally held in their last mentioned positions, which will close communication between the intermediate chamber and the outer atmosphere while opening communication between such intermediate chamber and the pressure chamber 35 communicating with the expansion reservoir, and in the construction shown such normal positions of the valves are maintained by the attractive force of a controlling magnet 30 upon its armature 41 which is fixed upon one end of the common valve stem 39 upon which both valves are mounted.

When the controlling valves are in their normal positions, the expansion reservoir 43 has free communication with the reciprocating motive chamber or cylinder 6 through the connecting pipe 42, pressure chamber 35 of the valve casing, inlet valve aperture thereof, its intermediate chamber 36, connecting pipe 14 leading from such intermediate chamber, heating coil 13, and motive fluid duct 9 of the piston stem 52 of the stationary piston 8.

The diagram shows a suitable bed plate 25, upon which is mounted the hollow main casing 15 which may be cylindrical in form and from the upper end of which projects vertically the piston stem 52, such piston stem having its lower end suitably secured in the center of the upper or end wall of the casing. The heating coil 13 is centrally located in the upper end of the main casing just underneath the piston stem. It may be described as a conical helix with convolutions disposed about a vertical axis coincident with the axis of the piston stem and gradually approaching such axis as they wind from the base to the top of the coil. The upper or outlet end of the heating coil may be secured in the lower end of the motive fluid duct 9, which passes centrally through the piston stem 52. The piston proper 8 is in the form of a collar or enlargement at the upper end of the piston stem 52. The vertical reciprocating cylinder or motive chamber 6 is in the form of an inverted cylindrical cup fitting over the piston proper so that the open end of the cylinder normally depends from the piston proper so as to form an annular inclosure or chamber surrounding the piston stem and open at its lower end. A semaphore-actuating rod 3 is secured in a suitable lug 50 or boss on the top of the motive cylinder and extends upward to and is connected with the signal semaphore 2 in a well known manner.

Centrally located in the bottom of the main casing and seated upon its bed plate 25 is a lamp 18, the flame 55 of which plays against or heats the high temperature junctures of two thermopiles 17 and 19 mounted upon, but insulated from, suitable brackets such as 21 and 20 respectively secured to the inner sides of the walls of the main casing. The combustion is supported by 60 air admitted through suitable air holes, such as 22. The heated gases of combustion, after passing the thermopile, rise to the heating coil and impinge or play against its convolutions so as to heat the coil and the motive fluid therein, and the coil is surrounded by an 65 inner casing 16 having its lower end mounted upon,

but insulated from, the thermopiles, while its upper end engages the inside of the top wall of the main casing. The top wall of the main casing is provided with a series of perforations or flue holes 12 arranged around the lower end of the piston stem and located just underneath the lower end of the cylindrical wall of the motive cylinder, so that the heated gases of combustion, after passing through and around the heating coil 13 and after giving up a portion of their heat thereto, rise through the flue holes 12 and thence into the lower 70 end of the annular chamber surrounding the piston stem and also at the same time rise around the outside of the motive cylinder. A supplementary casing 5 is mounted upon the upper end of the main casing 15 and surrounds the flue holes 12 and the motive 75 cylinder so as to retain the heated gases of combustion in contact with the motive cylinder and thus keep the cylinder in a heated condition. A central aperture 4 is provided at the upper end of the supplementary casing, through which the actuating rod 3 passes 80 and through which the gases of combustion are eventually discharged.

The result of the foregoing arrangement is that a portion of the heat of combustion is delivered to the thermopiles by radiation and by convection and is transmuted by such thermopiles into useful electrical energy, as will be hereinafter more fully pointed out, while the heat not transmuted by the thermopiles is confined to the heating coil 13 during its passage from the thermopiles to the flue holes 12 and is partially 90 utilized in heating the heating coil 13 and the motive fluid therein, and the remaining heat not utilized by the heating coil is applied to heat and to maintain in heated condition the piston stem, piston and motive cylinder.

The thermopile 19 continuously charges a storage battery 23 through a local circuit including the connecting wire 24, storage battery 23 and connecting wire 26. The valve-controlling magnet 30 is also included in a local circuit with the thermopile 19 and 105 with respect to current from such thermopile the magnet is in parallel with the storage battery 23 and its circuit, when closed, is traceable as follows: from one terminal of the thermopile through the conductor 24, magnet 30, conductor 29, contact finger 28 of the rear 110 track relay of the block B², such contact finger being normally held by attraction of the relay magnet 53 in contact with its co-operating contact stop 27, and thence through such contact stop 27 and the conductor 26 back to the opposite terminal of the thermopile. 115 The foregoing local circuit of the valve-controlling magnet 30 is normally closed by energization of the magnet 53 of the rear track relay of the railway block B², such rear track relay being normally energized by current transmitted through the rails l¹ and r² of the 120 block B², and from a thermopile 17^h comprised in the apparatus located at the advance end of the block B² and corresponding to the thermopile 17 already mentioned. The thermopile 17, like the thermopile 17^h, transmits current through a local circuit including, 125 the wire 33, storage battery 31 and wire 32, and thus charges such storage battery, while at the same time the thermopile 17 transmits current through the wire 33 to the advance end of the right rail r of the block B², thence through the track circuit of such block and 130

back to the advance end of the left rail 1 thereof, and thence through the wire 32 back to the opposite terminal of the thermopile.

When a train is present in any block of the system, 5 for instance in the block B² as illustrated, the magnet of the rear track relay at the rear end of such block is, by short-circuiting effect of the wheels and axles such as T of the train, deprived of energizing current so that its contact finger is retracted, by gravity or other 10 suitable retractive force, out of contacting position with its co-operating contact stop, thereby opening the local circuit of the valve-controlling magnet of the signaling apparatus located at the rear end of the block in which the train is present. As soon as the valve- 15 controlling magnet is thus de-energized, the controlling valves controlled by the magnet are, by gravity or any suitable retractive force, withdrawn from their normal positions so that the inlet valve 40 is closed and the outlet valve 38 is opened. If desired, the pressure of 20 the motive fluid alone may be relied upon for this retractive movement, since the pressure of motive fluid in the intermediate chamber 36 will always tend to open the outlet valve 38 while the pressure of fluid in the pressure chamber 35 will always tend to close the 25 inlet valve 40 as soon as the outlet valve 38 is opened. When the outlet valve 38 is opened and the inlet valve 40 is closed, the motive fluid, which up to this moment has been present in the motive cylinder 6 and has been holding its signal semaphore 2 in clear position 30 as illustrated by the signaling apparatus at the advance end of the block B², now escapes from the motive cylinder so as to reduce the pressure therein to normal or atmospheric pressure and permit the signal semaphore 2 to be moved, by its counterweight or by 35 any suitable means, to its danger position, while also sliding the motive cylinder down upon its piston to its danger position as illustrated by the apparatus at the rear end of the block B². Meantime the closure of the inlet valve 40 prevents the escape of motive 40 fluid from the expansion reservoir 43.

As soon as the train makes its exit from the block in which it is present, for instance the block B², the rear track relay at the rear end thereof is re-energized and replaces its contact finger such as 28 in position of contact with its co-operating contact stop 27, thus reclosing the local circuit of the valve-controlling magnet 30 and causing the controlling valves to be restored to their normal positions, which close the discharge outlet of the motive cylinder 6 and open communication between 45 such motive cylinder and the expansion reservoir 43. Thereupon motive fluid flows from the expansion reservoir 43 through the pipe 42, inlet valve 40, connecting pipe 14, heating coil 13 and piston stem 9 into the motive cylinder. The passage of the motive 50 fluid through the heating coil increases its temperature and its dynamic expansion, while the same result is effected by passage of the motive fluid through the heated piston stem 52 and into the heated motive cylinder 6, and not only are the temperature and dynamic 55 expansion of the motive fluid increased, but its temperature and volume are maintained by the heated condition of the motive cylinder and motive apparatus generally, after the motive cylinder has been moved by such dynamic expansion through its semaphore- 60 65 actuating stroke or movement.

A large saving in motive fluid results from the foregoing method of increasing its temperature and dynamic expansion.

Should either of the thermopiles be accidentally burned out or otherwise broken or damaged, its storage 70 battery would continue to supply current to the circuit normally supplied by such thermopile, until the thermopile could be repaired or replaced.

It is obvious that my invention may be embodied in various structures and systems within the principle and 75 scope thereof.

What I claim, and desire to secure by Letters Patent, is:-

1. Railway traffic-controlling apparatus comprising traffic-controlling means subject to actuation by converted thermal energy, a source of thermal energy, an energy-transmuter co-operative with the source of thermal energy to convert its energy into another form and co-operative with the traffic-controlling means to effect actuation of the same, and another energy-transmuter co-organized with the source of thermal energy and with the first energy-transmuter to convert into another form the waste thermal energy not converted by the first energy-transmuter, the second energy-transmuter being also co-operative with the traffic-controlling means to supply actuating energy thereto. 80
2. Railway traffic-controlling apparatus comprising traffic-controlling means, a source of thermal energy, and two energy-transmuters co-operative with the source of thermal energy to transmute its thermal energy, a given one of the energy-transmuters being co-operative with the traffic-controlling means to supply actuating energy thereto and the other transmuter being arranged to supply controlling energy for controlling the actuation of the traffic-controlling means. 95
3. Railway traffic-controlling apparatus comprising traffic-controlling means, a source of thermal energy, thermo-mechanical energy-transmuting means and thermo-electric energy-transmuting means both operative by the source of thermal energy and both in actuating relation to the traffic-controlling means. 100
4. Railway traffic-controlling apparatus comprising traffic-controlling means, a source of thermal energy, thermo-mechanical energy-transmuting means arranged to convert thermal energy from such source into mechanical energy 110 for actuating the traffic-controlling means, and thermo-electric energy-transmuting means arranged to convert thermal energy from the source of thermal energy into electrical energy and arranged to supply electrical energy for controlling the actuation of the traffic-controlling means. 115
5. Railway traffic-controlling apparatus comprising traffic-controlling means, a source of thermal energy, thermo-electric energy-transmuting means arranged to convert thermal energy from such source into electrical energy 120 and arranged to deliver such electrical energy to effect actuation of the traffic-controlling means, and thermo-mechanical energy-transmuting means arranged to convert the surplus thermal energy from the source of thermal energy not converted by the thermo-electric transmuting means and also arranged in actuating relation to the traffic-controlling means. 125
6. Railway traffic-controlling apparatus comprising traffic-controlling means, a source of heat, a thermopile operable by the source of heat and in actuating relation to the traffic-controlling means, and another energy-transmuting means also operable by the same source of heat and arranged to supply transmuted actuating energy to the traffic-controlling means. 130
7. Railway traffic-controlling apparatus comprising traffic-controlling means, a source of heat, energy-transmuting means operable by the source of heat and arranged to supply transmuted actuating energy to the traffic-controlling means, and a thermopile also operable by the same source of heat and arranged to supply electrical energy 140 for controlling the actuation of the traffic-controlling means by the first mentioned energy-transmuting means. 135
8. Railway traffic-controlling apparatus comprising traf-

- fic-controlling means, a source of heat, a thermopile operated by the source of heat, and in actuative relation to the traffic-controlling means, and thermo-mechanical energy-transmuting means arranged to transmute waste heat not converted by the thermopile and to supply actuative mechanical energy to the traffic-controlling means. 5
9. Railway traffic-controlling apparatus comprising traffic-controlling means, a source of heat, a thermopile operable by the source of heat, another energy-transmuting means receiving surplus heat not utilized by the thermopile and arranged to deliver transmuted actuative energy to the traffic-controlling means, the actuation of such traffic-controlling means being controllable by electrical energy from the thermopile. 10
15. 10. Railway traffic-controlling apparatus comprising traffic-controlling means, fluid-pressure motive apparatus in actuative relation to the traffic-controlling means, a source of heat arranged to heat the motive fluid of the fluid-pressure motive apparatus, a thermopile operable by the same source of heat, and a controlling circuit arranged to receive energy from the thermopile and in control of the actuation of the traffic-controlling means. 20
11. Railway traffic-controlling apparatus comprising traffic-controlling means, fluid-pressure motive apparatus in actuative relation to the traffic-controlling means, a source of heat arranged to heat the motive fluid of the fluid-pressure motive apparatus, thermo-electric energy-transmuting means operable by the same source of heat, and a controlling circuit arranged to receive energy from the thermo-electric energy-transmuter and in control of the actuation of the traffic-controlling means. 25
12. Railway traffic-controlling apparatus comprising railway traffic-controlling means, fluid-pressure motive apparatus in actuative relation to the traffic-controlling means, thermo-electric energy-transmuting means including a source of heat and co-operative with the fluid-pressure motive apparatus to heat the motive fluid thereof by the non-utilized heat passing off from the thermo-electric transmuting means, and a controlling electric circuit in control of the actuation of the traffic-controlling means and communicating with the thermo-electric transmuting means as a source of electrical energy. 30
13. Railway traffic-controlling apparatus comprising traffic-controlling means, fluid-pressure motive apparatus in actuative relation to the traffic-controlling means and including a source of motive fluid and a motive chamber and a conduit affording communication between the two, a source of heat arranged to heat the motive fluid in the conduit, a thermopile operable by the same source of heat, and a controlling electric circuit arranged to receive energy generated by the thermopile and disposed in controlling relation to the traffic-controlling means. 35
14. Railway traffic-controlling apparatus comprising traffic-controlling means, fluid-pressure motive apparatus in actuative relation to the traffic-controlling means and including a source of motive fluid and a motive chamber and a conduit affording communication between the two, a source of heat arranged to heat the motive chamber, a thermopile operable by the same source of heat, and a controlling electric circuit arranged to receive energy generated by the thermopile and disposed in controlling relation to the traffic-controlling means. 40
15. Railway traffic-controlling apparatus comprising traffic-controlling means, fluid-pressure motive apparatus in actuative relation to the traffic-controlling means and including a source of motive fluid and a motive chamber and a conduit affording communication between the two, a source of heat arranged to heat the motive chamber and the motive fluid in the conduit, a thermopile operable by the same source of heat, and a controlling electric circuit arranged to receive energy generated by the thermopile and disposed in controlling relation to the traffic-controlling means. 45
16. Railway traffic-controlling apparatus comprising traffic-controlling means, fluid-pressure motive apparatus in actuative relation to the traffic-controlling means and including a motive chamber, thermo-electric energy-transmuting means, a controlling electric circuit communicating with the thermo-electric energy-transmuter as a source of electricity and in control of the actuation of the traffic-controlling means, and one source of heat to operate the 50
- thermo-electric energy-transmuting means and to heat the motive chamber. 5
17. Railway traffic-controlling apparatus comprising traffic-controlling means, fluid-pressure motive apparatus in actuative relation to the traffic-controlling means and including a motive chamber, thermo-electric energy-transmuting means, a controlling electric circuit communicating with the thermo-electric energy-transmuter as a source of electricity and in control of the actuation of the traffic-controlling means, and one source of heat to operate the thermo-electric energy-transmuting means and to heat the motive chamber, and a casing inclosing the motive chamber. 85
18. Railway traffic-controlling apparatus comprising traffic-controlling means, fluid-pressure motive apparatus in actuative relation to the traffic-controlling means and including a motive chamber and a source of motive fluid and a motive fluid conduit leading from such source to such motive chamber, thermo-electric energy-transmuting means, an electric circuit communicating with such thermo-electric energy-transmuting means as a source of electrical energy and arranged in control of the actuation of the traffic-controlling means, and one source of heat arranged to supply thermal energy to the energy-transmuting means and to heat a portion of the motive fluid conduit, and a casing inclosing the heated portion of the motive fluid conduit. 90
19. Railway traffic-controlling apparatus comprising traffic-controlling means, fluid-pressure motive apparatus in actuative relation thereto and including a motive chamber and a source of motive fluid and a motive fluid conduit communicating between such source and chamber, a controlling electric circuit in control of the actuation of the traffic-controlling means, thermo-electric energy-transmuting means arranged to supply energy for the controlling circuit, a common source of heat for supplying thermal energy to the thermo-electric transmuter and for heating a portion of the motive fluid conduit and for heating the motive chamber, and casing walls inclosing the motive chamber and the heated portion of the motive fluid conduit. 100
20. Railway traffic-controlling apparatus comprising traffic-controlling means, fluid-pressure motive apparatus in actuative relation thereto and including a motive chamber and a source of motive fluid and a motive fluid conduit communicating between such source and chamber, a controlling electric circuit in control of the actuation of the traffic-controlling means, thermo-electric energy-transmuting means arranged to supply energy for the controlling circuit, a common source of heat for supplying thermal energy to the thermo-electric transmuter and for heating a portion of the motive fluid conduit and for heating the motive chamber, and casing walls inclosing the thermo-electric energy-transmuter and the motive chamber and the heated portion of the motive fluid conduit. 105
21. Railway traffic-controlling apparatus comprising traffic-controlling means disposed at a plurality of traffic-controlling points along the railway line, thermal energy-transmuting means in actuative relation to the traffic-controlling means at a given one of the traffic-controlling points, thermo-electric energy-transmuting means at such given point arranged to supply actuative electrical energy to the traffic-controlling means at another point, and a common source of heat for supplying thermal energy to the first mentioned actuative energy-transmuting means and to the thermo-electric energy-transmuter. 110
22. Railway traffic-controlling apparatus comprising traffic-controlling means disposed at a plurality of traffic-controlling points along a railway line, thermal energy-transmuting means in actuative relation to the traffic-controlling means at a given one of the traffic-controlling points, a thermopile at such given point arranged to supply actuative electrical energy to the traffic-controlling means at another point, and a common source of heat for supplying thermal energy to the first mentioned actuative energy-transmuting means and to the thermopile. 115
23. Railway traffic-controlling apparatus comprising traffic-controlling means located at a plurality of traffic-controlling points in proximity to a railway line, thermal energy-transmuting apparatus in actuative relation to the traffic-controlling means at a given one of the traffic-controlling points, another thermal energy-transmuting means 120

in actuating relation to the traffic-controlling means at another one of the traffic-controlling points, and a common source of heat for supplying thermal energy to both energy-transmuting means.

5 24. Railway traffic-controlling apparatus comprising traffic-controlling means located at a plurality of traffic-controlling points in proximity to a railway line, thermal energy-transmuting means in actuating relation to the traffic-controlling means at a given one of the traffic-controlling points, another thermal energy-transmuting means arranged to supply actuating energy to the traffic-controlling means at another one of the traffic-controlling points, and a source of heat arranged to supply thermal energy to a given one of the energy-transmuting means, the other energy-transmuting means being arranged to receive the surplus thermal energy not utilized by the given energy-transmuting means.

25. Railway traffic-controlling apparatus comprising traffic-controlling means located at a plurality of traffic-controlling points in proximity to a railway line, thermal energy-transmuting motive means in actuating relation to the traffic-controlling means at a given one of the traffic-controlling means at another one of the traffic-controlling points, controlling-points, a second thermal energy-transmuting means in actuating relation to the traffic-controlling means at another one of the traffic-controlling points, and a source of heat for supplying thermal energy to the second energy-transmuting means, the first mentioned energy-transmuting means being arranged to receive and transmute surplus thermal energy not utilized by the second energy-transmuter.

26. Railway traffic-controlling apparatus comprising traffic-controlling means located at a plurality of traffic-controlling points in proximity to a railway line, thermal energy-transmuting means arranged to supply actuating energy to the traffic-controlling means located at a given one of the traffic-controlling points, thermo-electric energy-transmuting means arranged to supply actuating electrical energy to the traffic-controlling means located at another one of the traffic-controlling points, and a source of heat for supplying thermal energy to the thermo-electric energy-transmuting means, the first mentioned thermal energy-transmuting means being arranged to receive and transmute surplus thermal energy not utilized by the thermo-electric energy-transmuter.

27. Railway traffic-controlling apparatus comprising traffic-controlling means located at a plurality of traffic-controlling points in proximity to a railway line, thermal energy-transmuting means arranged to supply actuating energy to the traffic-controlling means located at a given one of the traffic-controlling points, a thermopile arranged to supply actuating electrical energy to the traffic-controlling means located at another one of the traffic controlling points, and a source of heat for supplying thermal energy to the thermopile, the first mentioned thermal energy-transmuting means being arranged to receive and transmute thermal energy not utilized by the thermopile.

28. Railway traffic-controlling apparatus comprising traffic-controlling means located at a plurality of traffic-controlling points disposed in proximity to a railway line, actuating electric circuits in control of the traffic-controlling means at the various traffic-controlling points, and at a given traffic-controlling point two thermo-electric transmuters, one arranged to supply electricity to a controlling circuit in actuating control of the traffic-controlling means at the given point and the other arranged to supply electricity to a controlling circuit in actuating control of the traffic-controlling means at another one of the traffic-controlling points, and a common source of heat for supplying thermal energy to both the thermo-electric energy-transmuters.

29. Railway traffic-controlling apparatus comprising traffic-controlling means located at a plurality of traffic-controlling points disposed in proximity to a railway line, actuating electric circuits in control of the traffic-controlling means at the various traffic-controlling points, and at a given traffic-controlling point two thermopiles, one arranged to supply electricity to one of the circuits in actuating control of the traffic-controlling means at the given point and the other arranged to supply electricity to an actuating circuit in actuating control of the traffic-

controlling means at another one of the traffic-controlling points, and a common source of heat for supplying thermal energy to both the thermopiles.

30. Railway traffic-controlling apparatus comprising traffic-controlling means located at a plurality of traffic-controlling points disposed in proximity to a railway line, actuating electric circuits in control of the traffic-controlling means at the various traffic-controlling points, and at a given traffic-controlling point two thermo-electric transmuters, one arranged to supply electricity to a controlling circuit in actuating control of the traffic-controlling means at the given point and the other arranged to supply electricity to a controlling circuit in actuating control of the traffic-controlling means at another one of the traffic-controlling points, a common source of heat for supplying thermal energy to both the thermo-electric energy-transmuters, and a casing inclosing both the thermo-electric energy-transmuters.

31. Railway traffic-controlling apparatus comprising traffic-controlling means located at a plurality of traffic-controlling points in proximity to a railway line, at a given one of the traffic-controlling points a thermo-electric energy-transmuter arranged to deliver controlling electricity to the traffic-controlling means at another traffic-controlling point and also at the given traffic-controlling point another thermo-electric energy-transmuter arranged to deliver controlling actuating electricity to the traffic-controlling means at the given traffic-controlling point, and also at such given point a third thermal energy-transmuter arranged to convert thermal energy into motive energy and to deliver such motive energy to the traffic-controlling means at the given point, and at such given traffic-controlling point a source of heat common to both the thermo-electric energy-transmuters and to the third thermal energy-transmuter.

32. Railway traffic-controlling apparatus comprising traffic-controlling means located at a plurality of traffic-controlling points in proximity to a railway line, controlling electric circuits in controlling relation to the traffic-controlling means, at a given one of the traffic-controlling points a thermo-electric energy-transmuting means arranged to deliver energy to one of the controlling electric circuits and also at such given traffic-controlling point a second thermal energy-transmuter adapted to convert thermal energy into motive energy and to deliver such motive energy to the traffic-controlling means at such given point, and also at such given point a common source of heat arranged to deliver thermal energy both to the thermo-electric energy-transmuting means and to the second thermal energy-transmuter.

33. Railway traffic-controlling apparatus comprising traffic-controlling means located at a plurality of traffic-controlling points in proximity to a railway line, controlling electric circuits in controlling relation to the traffic-controlling means, at a given one of the traffic-controlling points a thermopile arranged to deliver energy to one of the controlling electric circuits and also at such given traffic-controlling point a second thermal energy-transmuter adapted to convert thermal energy into motive energy and to deliver such motive energy to the traffic-controlling means at such given point, and also at such given point a common source of heat arranged to deliver thermal energy both to the thermopile and to the second thermal energy-transmuter.

34. Railway traffic-controlling apparatus comprising traffic-controlling means located at a plurality of traffic-controlling points in proximity to a railway line, controlling electric circuits in controlling relation to the traffic-controlling means, at a given one of the traffic-controlling points a thermo-electric energy-transmuting means arranged to deliver energy to one of the controlling electric circuits and also at such given traffic-controlling point a second thermal energy-transmuter adapted to convert thermal energy into motive energy and to deliver such motive energy to the traffic-controlling means at such given point, and also at such given point a source of heat arranged to deliver thermal energy to the thermo-electric energy-transmuting means, the second thermal energy-transmuter being arranged to receive and transmute the surplus thermal energy not utilized by the thermo-electric energy-transmuting means.

35. Railway traffic-controlling apparatus comprising traffic-controlling means located at a plurality of traffic-controlling points in proximity to a railway line, controlling electric circuits in controlling relation to the traffic-controlling means, at a given one of the traffic-controlling points a thermopile arranged to deliver energy to one of the controlling electric circuits and also at such given traffic-controlling point a second thermal energy-transmuter adapted to convert thermal energy into motive energy and to deliver such motive energy to the traffic-controlling means at such given point, and also at such given point a source of heat arranged to deliver thermal energy to the thermopile, the second thermal energy-transmuter being arranged to receive and transmute the surplus thermal energy not utilized by the thermopile. 85
36. Railway traffic-controlling apparatus comprising traffic-controlling means, fluid-pressure motive means in actuating relation to the traffic-controlling means and including an electrically controllable controlling valve, a controlling electric circuit in controlling relation to the controlling valve, a thermo-electric energy-transmuter arranged to deliver electrical energy to the controlling circuit, and a source of thermal energy for the thermo-electric energy-transmuter. 90
37. Railway traffic-controlling apparatus comprising traffic-controlling means, fluid-pressure motive means in actuating relation to the traffic-controlling means and including an electrically controllable controlling valve, a controlling electric circuit in controlling relation to the controlling valve, a thermopile arranged to deliver electrical energy to the controlling circuit, and a source of thermal energy for the thermopile. 100
38. Railway traffic-controlling apparatus comprising traffic-controlling means, fluid-pressure motive apparatus in actuating relation thereto and including an electrically controllable controlling valve in controlling relation to the motive apparatus, a controlling electric circuit in control of the controlling valve, a thermo-electric energy-transmuter arranged to deliver electrical energy to the controlling circuit, and a common source of heat arranged to supply thermal energy to the thermo-electric energy-transmuter and to heat the motive fluid of the fluid-pressure motive apparatus. 110
39. Railway traffic-controlling apparatus comprising traffic-controlling means, fluid-pressure motive apparatus including a source of motive fluid, and fluid-pressure energy-transmuting means constituting a motor proper in actuating relation to the traffic-controlling means and a motive fluid conduit leading from the source of motive fluid to the motor proper and an electrically controllable controlling valve interposed in such conduit, a controlling electric circuit in control of the electrically controllable controlling valve, thermo-electric energy-transmuter means arranged to supply electricity to the controlling circuit, and a common source of heat arranged to supply thermal energy to the thermo-electric energy-transmuter and to heat the motive fluid in the motive fluid conduit. 120
40. Railway traffic-controlling apparatus comprising traffic-controlling means, fluid-pressure motive apparatus including a source of motive fluid and fluid-pressure energy-transmuting means constituting a motor proper in actuating relation to the traffic-controlling means and a motive fluid conduit leading from the source of motive fluid to the motor proper and an electrically controllable controlling valve interposed in such conduit, a controlling electric circuit in control of the electrically controllable controlling valve, thermo-electric energy-transmuter means arranged to supply electricity to the controlling circuit, and a common source of heat arranged to supply thermal energy to the thermo-electric energy-transmuter and to heat the motive fluid conduit at a point between its controlling valve and the motor proper. 130
41. Railway traffic-controlling apparatus comprising traffic-controlling means, fluid-pressure motive apparatus including a source of motive fluid and fluid-pressure energy-transmuting means constituting a motor proper in actuating relation to the traffic-controlling means and a motive fluid conduit leading from the source of motive fluid to the motor proper and an electrically controllable controlling valve interposed in such conduit, a controlling electric circuit in control of the electrically controllable controlling valve, thermo-electric energy-transmuter means arranged to supply electricity to the controlling circuit, and a common source of heat arranged to supply thermal energy to the thermo-electric energy-transmuter and to heat the motive fluid in the motive fluid conduit. 140
42. Railway traffic-controlling apparatus comprising traffic-controlling means, fluid-pressure motive apparatus including a source of motive fluid and fluid-pressure energy-transmuting means constituting a motor proper in actuating relation to the traffic-controlling means and a motive fluid conduit leading from the source of motive fluid to the motor proper and an electrically controllable controlling valve interposed in such conduit, a controlling electric circuit in control of the electrically controllable controlling valve, thermo-electric energy-transmuter means arranged to supply electricity to the controlling circuit, and a source of heat arranged to supply thermal energy to the thermo-electric energy-transmuter, the motive fluid conduit being arranged to be heated by surplus heat not converted by the thermo-electric energy-transmuter. 150
43. Railway traffic-controlling apparatus comprising traffic-controlling means located at a plurality of traffic-controlling points disposed in proximity to a railway line, one or more traffic-controlling circuits in control of the traffic-controlling means, a conservator of electrical energy arranged to deliver electricity to one of the traffic-controlling circuits, at a given one of the traffic-controlling points a thermo-electric energy-transmuter arranged to transmute thermal energy into electrical energy and to charge such conservator of electricity, also at such given traffic-controlling point a second thermal energy-transmuting means arranged to deliver actuating energy to the traffic-controlling means at such given point, and also at such given point a common source of thermal energy for both the thermo-electric energy-transmuter and for the second thermal energy-transmuter. 160
44. Railway traffic-controlling apparatus comprising traffic-controlling means located at a plurality of traffic-controlling points disposed in proximity to a railway line, one or more traffic-controlling circuits in control of the traffic-controlling means, a storage battery of electrical energy arranged to deliver electricity to one of the traffic-controlling circuits, at a given one of the traffic-controlling points a thermopile arranged to transmute thermal energy into electrical energy and to charge such storage battery of electricity, also at such given traffic-controlling point a second thermal energy-transmuting means arranged to deliver actuating energy to the traffic-controlling means at such given point, and also at such given point a common source of thermal energy for both the thermopile and for the second thermal energy transmuter. 170
45. Railway traffic-controlling apparatus comprising traffic-controlling means, actuating means therefor comprising thermal energy-transmuting means to convert thermal energy into motive energy for the traffic-controlling means, a traffic-controlling electric circuit in control of the actuation of the traffic-controlling means, a source of electrical energy for the controlling circuit, a thermo-electric energy-transmuter arranged to charge the source of electricity, and a common source of heat arranged to supply thermal energy both to the thermo-electric energy-transmuter and to the first mentioned thermal energy-transmuting means. 180
46. Railway traffic-controlling apparatus comprising traffic-controlling means, located at a fixed traffic-controlling point on a railway track and arranged in control of traffic along the track fluid-pressure motive means in actuating co-operation therewith, a motive fluid conduit leading to the motive means, a source of motive fluid for the conduit, and a source of heat arranged to heat the motive fluid conduit. 190
47. Railway traffic-controlling apparatus comprising traffic-controlling means, located at a fixed traffic-controlling point on a railway track and arranged in control of traffic along the track fluid-pressure motive means in actuating relation to the traffic-controlling means, a motive fluid conduit leading to the motive means, a source of motive fluid for the conduit, and a source of heat arranged to heat the motive fluid conduit. 200

- 8
- motive fluid for the conduit, a controlling valve interposed in the conduit, and a source of heat arranged to heat the conduit and the motive fluid therein at a point between its controlling valve and the fluid-pressure motive means.
- 5 48. Railway traffic-controlling apparatus comprising traffic-controlling means, located at a fixed traffic-controlling point on a railway track and arranged in control of traffic along the track fluid-pressure motive means in actuating co-operation with the traffic-controlling means, a 85 source of motive fluid, a conduit leading from such source to the motive means, a source of heat arranged to heat a portion of the motive fluid conduit, and a casing surrounding the heated portion thereof.
- 10 49. Railway traffic-controlling apparatus comprising traffic-controlling means, located at a fixed traffic-controlling point on a railway track and arranged in control of traffic along the track a source of heat, fluid-pressure motive means in actuating co-operation with the traffic-controlling means, a source of motive fluid, a motive fluid conduit leading from such source to the motive means and including one or more convolutions arranged to be heated by the source of heat. 90
- 15 50. Railway traffic-controlling apparatus comprising traffic-controlling means, located at a fixed traffic-controlling point on a railway track and arranged in control of traffic along the track a source of heat, fluid-pressure motive means in actuating co-operation with the traffic-controlling means, a source of motive fluid, a motive fluid conduit leading from such source to the motive means and including a heating coil arranged to be heated by the source of heat, and a casing inclosing the heating coil. 95
- 20 51. Railway traffic-controlling apparatus comprising traffic-controlling means, a source of heat, fluid-pressure motive means in actuating co-operation with the traffic-controlling means, a source of motive fluid, a motive fluid conduit leading from such source to the motive means and including one or more convolutions arranged to be heated by the source of heat, and a controlling valve interposed in the motive fluid conduit between its source of motive fluid and its heating convolutions. 100
- 25 52. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, and a source of motive fluid communicating with the motive chamber. 105
- 30 53. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a casing inclosing the motive chamber, and a source of motive fluid communicating with the motive chamber. 110
- 35 54. Railway traffic-controlling apparatus comprising traffic-controlling means, a source of heat, a fluid-pressure motive chamber in actuating relation to the traffic-controlling means and disposed above the source of heat and having its lower side open so that both its outer and its inner walls may be heated by the source of heat. 115
- 40 55. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a source of motive fluid communicating with the motive chamber and means for controlling such communication between the source of motive fluid and the motive chamber. 120
- 45 56. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a motive fluid conduit leading to the motive chamber and also arranged to be heated by the source of heat, and a source of heat arranged to heat the motive fluid conduit leading to the motive chamber. 125
- 50 57. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a motive fluid conduit leading to the motive chamber and also arranged to be heated by the source of heat, a source of motive fluid communicating with the motive fluid conduit, and inclosing walls surrounding the motive chamber and the heated portion of the motive fluid conduit. 130
- 55 58. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a source of motive fluid, a motive fluid conduit leading from such source to the motive chamber and including a portion arranged to be heated by the source of heat, and a controlling valve interposed in the motive fluid conduit. 135
- 60 59. Railway traffic-controlling apparatus comprising traffic-controlling means, located at a fixed traffic-controlling point on a railway track and arranged in control of traffic along the track a source of heat, a fluid-pressure motive chamber in actuating co-operation with the traffic-controlling means and arranged to be heated by the source of heat, a source of motive fluid, a motive fluid conduit leading from such source to the motive chamber and including a portion arranged to be heated by the source of heat, and a controlling valve interposed in the motive fluid conduit between its heated portion and its source of motive fluid. 140
- 65 60. Railway traffic-controlling apparatus comprising traffic-controlling means located at a plurality of traffic-controlling points in proximity to a railway line, one or more controlling electric circuits in control of the traffic-controlling means, at a given one of the traffic-controlling points, fluid-pressure motive apparatus in actuating relation to the traffic-controlling means at such given point, 145 a source of motive fluid communicating with the fluid-pressure motive means through suitable pressure-reducing means, at the given traffic-controlling point thermo-electric energy-transmuting means arranged to supply energy to one of the traffic-controlling circuits, and also at such given traffic-controlling point a common source of heat arranged both to heat the fluid-pressure motive apparatus and to supply thermal energy to the thermo-electric energy-transmuter. 150
- 70 61. Railway traffic-controlling apparatus comprising traffic-controlling means located at a plurality of traffic-controlling points in proximity to a railway line, one or more controlling electric circuits in control of the traffic-controlling means, at a given one of the traffic-controlling points fluid-pressure motive apparatus in actuating relation to the traffic-controlling means at such point, a motive fluid reservoir communicating with the fluid-pressure motive apparatus, a source of motive fluid communicating with the reservoir through suitable pressure-reducing means, at the given traffic-controlling point a thermo-electric energy-transmuting means arranged to supply energy to one of the traffic-controlling circuits, and also at the given traffic-controlling point a common source of heat arranged both to heat the fluid-pressure motive apparatus and to supply thermal energy to the thermo-electric energy-transmuter. 155
- 75 62. Railway traffic-controlling apparatus comprising traffic-controlling means, located at a fixed traffic-controlling point on a railway track and arranged in control of traffic along the track a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive fluid after it has passed from the reservoir. 160
- 80 63. Railway traffic-controlling apparatus comprising

- traffic-controlling means, located at a fixed traffic-controlling point on a railway track and arranged in control of traffic along the track a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive fluid conduit. 85
- 10 64. Railway traffic-controlling apparatus comprising traffic-controlling means, located at a fixed traffic-controlling point on a railway track and arranged in control of traffic along the track a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive chamber. 90
- 15 65. Railway traffic-controlling apparatus comprising traffic-controlling means, a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive chamber. 95
- 20 66. Railway traffic-controlling apparatus comprising traffic-controlling means, located at a fixed traffic-controlling point on a railway track and arranged in control of traffic along the track a fluid-pressure motive chamber in actuating relation thereto, a source of motive fluid, a motive fluid reservoir communicating with the source of motive fluid through suitable pressure-reducing means, a motive fluid conduit leading from the motive fluid reservoir to the fluid-pressure motive chamber, a controlling valve interposed in the motive fluid conduit, and a source of heat arranged to heat the motive fluid after it has passed through the controlling valve. 100
- 25 67. Railway traffic-controlling apparatus comprising traffic-controlling means located at a plurality of traffic-controlling points in proximity to a railway line, one or more controlling electric circuits in control of the traffic-controlling means, at a given one of the traffic-controlling points a fluid-pressure motive apparatus in actuating co-operation with the traffic-controlling means and also at such given point a thermo-electric energy-transmuting means arranged to supply energy to one of the controlling circuits, and also at the given traffic-controlling point a source of heat arranged both to heat the motive fluid of the fluid-pressure motive apparatus and to supply thermal energy to the thermo-electric energy-transmuter. 105
- 30 68. Railway traffic-controlling apparatus comprising traffic-controlling means located at a plurality of traffic-controlling points in proximity to a railway line, traffic-controlling circuits in control of the traffic-controlling means, at a given one of the traffic-controlling points fluid-pressure motive apparatus in actuating co-operation with the traffic-controlling means at such point, and also at the given traffic-controlling point a thermo-electric energy-transmuting apparatus including a source of thermal energy and arranged to deliver its surplus or non-utilized heat to the fluid-pressure motive apparatus to warm the motive fluid thereof, and arranged to deliver its energy to one of the traffic-controlling circuits. 110
- 35 69. Railway signaling apparatus comprising signal-indicating means subject to actuation by converted thermal energy, a source of thermal energy, an energy-transmuter co-operative with the source of thermal energy to convert its energy into another form and co-operative with the signal-indicating means to effect actuation of the same, and another energy-transmuter co-organized with the source of thermal energy and with the first energy-transmuter to convert into another form the waste thermal energy not converted by the first energy-transmuter, the second energy-transmuter being also co-operative with the signal-indicating means to supply actuating energy thereto. 115
- 40 70. Railway signaling apparatus comprising signal-indicating means, a source of thermal energy, and two energy-transmuters co-operative with the source of thermal energy to transmute its thermal energy, a given one of the energy-transmuters being co-operative with the signal-indicating means to supply actuating energy thereto and the other transmuter being arranged to supply controlling energy for controlling the actuation of the signal-indicating means. 120
- 45 71. Railway signaling apparatus comprising signal-indicating means, a source of thermal energy, thermo-mechanical energy-transmitting means arranged to convert thermal energy from such source into mechanical energy for actuating the signal-indicating means, and thermo-electric energy-transmuting means arranged to convert thermal energy from the source of thermal energy into electrical energy and arranged to supply electrical energy for controlling the actuation of the signal-indicating means. 125
- 50 72. Railway signaling apparatus comprising signal-indicating means, a source of thermal energy, thermo-mechanical energy-transmuting means arranged to convert thermal energy from such source into mechanical energy for actuating the signal-indicating means, and thermo-electric energy-transmuting means arranged to convert thermal energy from the source of thermal energy into electrical energy and arranged to supply electrical energy for controlling the actuation of the signal-indicating means. 130
- 55 73. Railway signaling apparatus comprising signal-indicating means, a source of thermal energy, thermo-electric energy-transmuting means arranged to convert thermal energy from such source into electrical energy and arranged to deliver such electrical energy to effect actuation of the signal-indicating means, and thermo-mechanical energy-transmuting means arranged to convert the surplus thermal energy from the source of thermal energy not converted by the thermo-electric transmuting means and also arranged in actuating relation to the signal-indicating means. 135
- 60 74. Railway signaling apparatus comprising signal-indicating means, a source of heat, a thermopile operable by the source of heat and in actuating relation to the signal-indicating means, and another energy-transmuting means also operable by the same source of heat and arranged to supply transmuted actuating energy to the signal-indicating means. 140
- 65 75. Railway signaling apparatus comprising signal-indicating means, a source of heat, energy-transmuting means operable by the source of heat and arranged to supply transmuted actuating energy to the signal-indicating means, and a thermopile also operable by the same source of heat and arranged to supply electrical energy for controlling the actuation of the signal-indicating means by the first mentioned energy-transmuting means. 145
- 70 76. Railway signaling apparatus comprising signal-indicating means, a source of heat, a thermopile operated by the source of heat and in actuating relation to the signal-indicating means, and thermo-mechanical energy-transmuting means arranged to transmute waste heat not converted by the thermopile and to supply actuating mechanical energy to the signal-indicating means. 150
- 75 77. Railway signaling apparatus comprising signal-indicating means, a source of heat, a thermopile operable by the source of heat, another energy-transmuting means receiving surplus heat not utilized by the thermopile and arranged to deliver transmuted actuating energy to the signal-indicating means, the actuation of such signal-indicating means being controllable by electrical energy from the thermopile. 155
- 80 78. Railway signaling apparatus comprising signal-indicating means, fluid-pressure motive apparatus in actuating relation to the signal-indicating means, a source of heat arranged to heat the motive fluid of the fluid-pressure motive apparatus, a thermopile operable by the same source of heat, and a controlling circuit arranged to receive energy from the thermopile and in control of the actuation of the signal-indicating means. 160
- 85 79. Railway signaling apparatus comprising signal-indicating means, fluid-pressure motive apparatus in actuating relation to the signal-indicating means, a source of heat arranged to heat the motive fluid of the fluid-pressure motive apparatus, thermo-electric energy-transmuting means operable by the same source of heat, and a controlling circuit arranged to receive energy from the thermo-electric energy-transmuter and in control of the actuation of the signal-indicating means. 165
- 90 80. Railway signaling apparatus comprising railway

- 10
- signal-indicating means, in actuation relation to the signal-indicating means, thermo-electric energy-transmuting means including a source of heat and co-operative with the fluid-pressure motive apparatus to heat the motive fluid thereof by the non-utilized heat passing off from the thermo-electric transmuting means, and a controlling electric circuit in control of the actuation of the signal-indicating means and communicating with the thermo-electric transmuting means as a source of electrical energy. 10
81. Railway signaling apparatus comprising signal-indicating means, fluid-pressure motive apparatus in actuation relation to the signal-indicating means and including a source of motive fluid and a motive chamber and a conduit affording communication between the two, a source of heat arranged to heat the motive fluid in the conduit, a thermopile operable by the same source of heat, and a controlling electric circuit arranged to receive energy generated by the thermopile and disposed in controlling relation to the signal-indicating means. 15
82. Railway signaling apparatus comprising signal-indicating means, fluid-pressure motive apparatus in actuation relation to the signal-indicating means and including a source of motive fluid and a motive chamber and a conduit affording communication between the two, a source of heat arranged to heat the motive chamber, a thermopile operable by the same source of heat, and a controlling electric circuit arranged to receive energy generated by the thermopile and disposed in controlling relation to the signal-indicating means. 20
83. Railway signaling apparatus comprising signal-indicating means, fluid-pressure motive apparatus in actuation relation to the signal-indicating means and including a source of motive fluid and a motive chamber and a conduit affording communication between the two, a source of heat arranged to heat the motive chamber and the motive fluid in the conduit, a thermopile operable by the same source of heat, and a controlling electric circuit arranged to receive energy generated by the thermopile and disposed in controlling relation to the signal-indicating means. 25
84. Railway signaling apparatus comprising signal-indicating means, fluid-pressure motive apparatus in actuation relation to the signal-indicating means and including a motive chamber, thermo-electric energy-transmuting means, a controlling electric circuit communicating with the thermo-electric energy-transmuter as a source of electricity and in control of the actuation of the signal-indicating means, and one source of heat to operate the thermo-electric energy-transmuting means and to heat the motive chamber. 30
85. Railway signaling apparatus comprising signal-indicating means, fluid-pressure motive apparatus in actuation relation to the signal-indicating means and including a motive chamber, thermo-electric energy-transmuting means, a controlling electric circuit communicating with the thermo-electric energy-transmuter as a source of electricity and in control of the actuation of the signal-indicating means, and one source of heat to operate the thermo-electric energy-transmuting means and to heat the motive chamber, and a casing inclosing the motive chamber. 35
86. Railway signaling apparatus comprising signal-indicating means, fluid-pressure motive apparatus in actuation relation to the signal-indicating means and including a motive chamber and a source of motive fluid and a motive fluid conduit leading from such source to such motive chamber, thermo-electric energy-transmuting means, an electric circuit communicating with such thermo-electric energy-transmuting means as a source of electrical energy and arranged in control of the actuation of the signal-indicating means, and one source of heat arranged to supply thermal energy to the energy-transmuting means and to heat a portion of the motive fluid conduit, and a casing inclosing the heated portion of the motive fluid conduit. 40
87. Railway signaling apparatus comprising signal-indicating means, fluid-pressure motive apparatus in actuation relation thereto and including a motive chamber and a source of motive fluid and a motive fluid conduit communicating between such source and chamber, a control- 45
- ing electric circuit in control of the actuation of the signal-indicating means, thermo-electric energy-transmuting means arranged to supply energy for the controlling circuit, a common source of heat for supplying thermal energy to the thermo-electric transmuter and for heating a portion of the motive fluid conduit and for heating the motive chamber, and casing walls inclosing the motive chamber and the heated portion of the motive fluid conduit. 50
88. Railway signaling apparatus comprising signal-indicating means, fluid-pressure motive apparatus in actuation relation thereto and including a motive chamber and a source of motive fluid and a motive fluid conduit communicating between such source and chamber, a controlling electric circuit in control of the actuation of the signal-indicating means, thermo-electric energy-transmuting means arranged to supply energy for the controlling circuit, a common source of heat for supplying thermal energy to the thermo-electric transmuter and for heating a portion of the motive fluid conduit and for heating the motive chamber, and casing walls inclosing the thermo-electric energy-transmuter and the motive chamber and the heated portion of the motive fluid conduit. 55
89. Railway signaling apparatus comprising signal-indicating means disposed at a plurality of signal-indicating points along the railway line, thermal energy-transmuting means in actuation relation to the signal-indicating means at a given one of the signal-indicating points, thermo-electric energy-transmuting means at such given point arranged to supply actuating electrical energy to the signal-indicating means at another point, and a common source of heat for supplying thermal energy to the first mentioned actuating energy-transmuting means and to the thermo-electric energy-transmuter. 60
90. Railway signaling apparatus comprising signal-indicating means disposed at a plurality of signal-indicating points along a railway line, thermal energy-transmuting means in actuation relation to the signal-indicating means at a given one of the signal-indicating points, a thermopile at such given point arranged to supply actuating electrical energy to the signal-indicating means at another point, and a common source of heat for supplying thermal energy to the first mentioned actuating energy-transmuting means and to the thermopile. 65
91. Railway signaling apparatus comprising signal-indicating means located at a plurality of signal-indicating points in proximity to a railway line, thermal energy-transmuting apparatus in actuation relation to the signal-indicating means at a given one of the signal-indicating points, another thermal energy-transmuting means in actuation relation to the signal-indicating means at another one of the signal-indicating points, and a common source of heat for supplying thermal energy to both energy-transmuting means. 70
92. Railway signaling apparatus comprising signal-indicating means located at a plurality of signaling points in proximity to a railway line, thermal energy-transmuting means in actuation relation to the signal-indicating means at a given one of the signaling points, another thermal energy-transmuting means arranged to supply actuating energy to the signal-indicating means at another one of the signaling points, and a source of heat arranged to supply thermal energy to a given one of the energy-transmuting means, the other energy-transmuting means being arranged to receive the surplus thermal energy not utilized by the given energy-transmuting means. 75
93. Railway signaling apparatus comprising signal-indicating means located at a plurality of signaling points in proximity to a railway line, thermal energy-transmuting motive means in actuation relation to the signal-indicating means at a given one of the signaling points, a second thermal energy-transmuting means in actuation relation to the signal-indicating means at another one of the signaling points, and a source of heat for supplying thermal energy to the second energy-transmuting means, the first mentioned energy-transmuting means being arranged to receive and transmute surplus thermal energy not utilized by the second energy-transmuter. 80
94. Railway signaling apparatus comprising signal-indicating means located at a plurality of signaling points in 85

- proximity to a railway line, thermal energy-transmuting means arranged to supply actuating energy to the signal-indicating means located at a given one of the signaling points, thermo-electric energy-transmuting means arranged to supply actuating electrical energy to the signal-indicating means located at another one of the signaling points, and a source of heat for supplying thermal energy to the thermo-electric energy-transmuting means, the first mentioned thermal energy-transmuting means being arranged to receive and transmute surplus thermal energy not utilized by the thermo-electric energy-transmuter. 5
95. Railway signaling apparatus comprising signal-indicating means located at a plurality of signaling points in proximity to a railway line, thermal energy-transmuting means arranged to supply actuating energy to the signal-indicating means located at a given one of the signaling points, a thermopile arranged to supply actuating electrical energy to the signal-indicating means located at another one of the signaling points, and a source of heat for supplying thermal energy to the thermopile, the first mentioned thermal energy-transmuting means being arranged to receive and transmute thermal energy not utilized by the thermopile. 10
96. Railway signaling apparatus comprising signal-indicating means located at a plurality of signaling points disposed in proximity to a railway line, actuating electric circuits in control of the signal-indicating means at the various signaling points, and at a given signaling point two thermo-electric transmuters, one arranged to supply electricity to a controlling circuit in actuating control of the signal-indicating means at the given point and the other arranged to supply electricity to a controlling circuit in actuating control of the signal-indicating means at another one of the signaling points, and a common source of heat for supplying thermal energy to both the thermo-electric energy-transmuters. 15
97. Railway signaling apparatus comprising signal-indicating means located at a plurality of signaling points disposed in proximity to a railway line, actuating electric circuits in control of the signal-indicating means at the various signaling points, and at a given signaling point two thermopiles, one arranged to supply electricity to one of the circuits in actuating control of the signal-indicating means at the given point and the other arranged to supply electricity to an actuating circuit in actuating control of the signal-indicating means at another one of the signaling points, and a common source of heat for supplying thermal energy to both the thermopiles. 20
98. Railway signaling apparatus comprising signal-indicating means located at a plurality of signaling points disposed in proximity to a railway line, actuating electric circuits in control of the signal-indicating means at the various signaling points, and at a given signaling point two thermo-electric transmuters, one arranged to supply electricity to a controlling circuit in actuating control of the signal-indicating means at the given point and the other arranged to supply electricity to a controlling circuit in actuating control of the signal-indicating means at another one of the signaling points, a common source of heat for supplying thermal energy to both the thermo-electric energy-transmuters, and a casing inclosing both the thermo-electric energy-transmuters. 25
99. Railway signaling apparatus comprising signal-indicating means located at a plurality of signaling points in proximity to a railway line, at a given one of the signaling points a thermo-electric energy-transmuter arranged to deliver controlling electricity to the signal-indicating means at another signaling point and also at the given signaling point another thermo-electric energy-transmuter arranged to deliver controlling actuating electricity to the signal-indicating means at the given signaling point, and also at such given point a third thermal energy-transmuter arranged to convert thermal energy into motive energy and to deliver such motive energy to the signal-indicating means at the given point, and at such given signaling point a source of heat common to both the thermo-electric energy-transmuters and to the third thermal energy-transmuter. 30
100. Railway signaling apparatus comprising signal-indicating means located at a plurality of signaling points in proximity to a railway line, controlling electric circuits in controlling relation to the signal-indicating means, at a given one of the signaling points a thermo-electric energy-transmuting means arranged to deliver energy to one of the controlling electric circuits and also at such given signaling point a second thermal energy-transmuter adapted to convert thermal energy into motive energy and to deliver such motive energy to the signal-indicating means at such given point, and also at such given point a common source of heat arranged to deliver thermal energy both to the thermo-electric energy-transmuting means and to the second thermal energy-transmuter. 35
101. Railway signaling apparatus comprising signal-indicating means located at a plurality of signaling points in proximity to a railway line, controlling electric circuits in controlling relation to the signal-indicating means, at a given one of the signaling points a thermopile arranged to deliver energy to one of the controlling electric circuits and also at such given signaling point a second thermal energy-transmuter adapted to convert thermal energy into motive energy and to deliver such motive energy to the signal-indicating means at such given point, and also at such given point a common source of heat arranged to deliver thermal energy both to the thermopile and to the second thermal energy-transmuter. 40
102. Railway signaling apparatus comprising signal-indicating means located at a plurality of signaling points in proximity to a railway line, controlling electric circuits in controlling relation to the signal-indicating means, at a given one of the signaling points a thermo-electric energy-transmuting means arranged to deliver energy to one of the controlling electric circuits and also at such given signaling point a second thermal energy-transmuter adapted to convert thermal energy into motive energy and to deliver such motive energy to the signal-indicating means at such given point, and also at such given point a common source of heat arranged to deliver thermal energy both to the thermopile and to the second thermal energy-transmuter. 45
103. Railway signaling apparatus comprising signal-indicating means located at a plurality of signaling points in proximity to a railway line, controlling electric circuits in controlling relation to the signal-indicating means, at a given one of the signaling points a thermopile arranged to deliver energy to one of the controlling electric circuits and also at such given signaling point a second thermal energy-transmuter adapted to convert thermal energy into motive energy and to deliver such motive energy to the signal-indicating means at such given point, and also at such given point a common source of heat arranged to deliver thermal energy to the thermopile, the second thermal energy-transmuter being arranged to receive and transmute the surplus thermal energy not utilized by the thermo-electric energy-transmuting means. 50
104. Railway signaling apparatus comprising signal-indicating means, fluid-pressure motive means in actuating relation to the signal-indicating means and including an electrically controllable controlling valve, a controlling electric circuit in controlling relation to the controlling valve, a thermo-electric energy-transmuter arranged to deliver electrical energy to the controlling circuit, and a source of thermal energy for the thermo-electric energy-transmuter. 55
105. Railway signaling apparatus comprising signal-indicating means, fluid-pressure motive means in actuating relation to the signal-indicating means, and including an electrically controllable controlling valve, a controlling electric circuit in controlling relation to the controlling valve, a thermopile arranged to deliver electrical energy to the controlling circuit, and a source of thermal energy for the thermopile. 60
106. Railway signaling apparatus comprising signal-indicating means, fluid-pressure motive apparatus in actuating relation thereto and including an electrically controllable controlling valve in controlling relation to the motive apparatus, a controlling electric circuit in control of the controlling valve, a thermo-electric energy-transmuting means arranged to deliver electrical energy to the controlling circuit, and a common source of heat arranged to sup- 65

- ply thermal energy to the thermo-electric energy-transmuter and to heat the motive fluid of the fluid-pressure motive apparatus.
107. Railway signaling apparatus comprising signal-indicating means, fluid-pressure motive apparatus including a source of motive fluid, and fluid-pressure energy-transmuting means constituting a motor proper in actuating relation to the signal-indicating means and a motive fluid conduit leading from the source of motive fluid to the motor proper and an electrically controllable controlling valve interposed in such conduit, a controlling electric circuit in control of the electrically controllable controlling valve, thermo-electric energy-transmuting means arranged to supply electricity to the controlling circuit, and a common source of heat arranged to supply thermal energy to the thermo-electric energy-transmuter and to heat the motive fluid in the motive fluid conduit. 85
108. Railway signaling apparatus comprising signal-indicating means, fluid-pressure motive apparatus including a source of motive fluid and fluid-pressure energy-transmuting means constituting a motor proper in actuating relation to the signal-indicating means and a motive fluid conduit leading from the source of motive fluid to the motor proper and an electrically controllable controlling valve interposed in such conduit, a controlling electric circuit in control of the electrically controllable controlling valve, thermo-electric energy-transmuting means arranged to supply electricity to the controlling circuit, and a common source of heat arranged to supply thermal energy to the thermo-electric energy-transmuter and to heat the motive fluid conduit at a point between its controlling valve and the motor proper. 90
109. Railway signaling apparatus comprising signal-indicating means, fluid-pressure motive apparatus including a source of motive fluid and fluid-pressure energy-transmuting means constituting a motor proper in actuating relation to the signal-indicating means and a motive fluid conduit leading from the source of motive fluid to the motor proper and an electrically controllable controlling valve interposed in such conduit, a controlling electric circuit in control of the electrically controllable controlling valve, thermo-electric energy-transmuting means arranged to supply electricity to the controlling circuit, and a source of heat arranged to supply thermal energy to the thermo-electric energy-transmuter, the motive fluid conduit being arranged to be heated by surplus heat not converted by the thermo-electric energy-transmuter. 100
110. Railway signaling apparatus comprising signal-indicating means, fluid-pressure motive apparatus including a source of motive fluid and fluid-pressure energy-transmuting means constituting a motor proper in actuating relation to the signal-indicating means and a motive fluid conduit leading from the source of motive fluid to the motor proper and an electrically controllable controlling valve interposed in such conduit, a controlling electric circuit in control of the electrically controllable controlling valve, thermo-electric energy-transmuting means arranged to supply electricity to the controlling circuit, and a source of heat arranged to supply thermal energy to the thermo-electric energy-transmuter, the motive fluid conduit having a portion between its controlling valve and the motor proper arranged to be heated by surplus heat not utilized by the thermo-electric energy-transmuter. 110
111. Railway signaling apparatus comprising signal-indicating means located at a plurality of signaling points disposed in proximity to a railway line, one or more signaling circuits in control of the signal-indicating means, a conservator of electrical energy arranged to deliver electricity to one of the signaling circuits, at a given one of the signaling points a thermo-electric energy-transmuter arranged to transmute thermal energy into electrical energy and to charge such conservator of electricity, also at such given signaling point a second thermal energy-transmuting means arranged to deliver actuating energy to the signal-indicating means at such given point, and also at such given point a common source of thermal energy for both the thermo-electric energy-transmuter and for the second thermal energy-transmuter. 115
112. Railway signaling apparatus comprising signal-indicating means located at a plurality of signaling points disposed in proximity to a railway line, one or more signaling circuits in control of the signal-indicating means, a storage battery of electrical energy arranged to deliver electricity to one of the signaling circuits, at a given one of the signaling points a thermopile arranged to transmute thermal energy into electrical energy and to charge such storage battery of electricity, also at such given signaling point a second thermal energy-transmuting means arranged to deliver actuating energy to the signal-indicating means at such given point, and also at such given point a common source of thermal energy for both the thermopile and for the second thermal energy-transmuter. 120
113. Railway signaling apparatus comprising signal-indicating means, actuating means therefor comprising thermal energy-transmuting means to convert thermal energy into motive energy for the signal-indicating means, a signaling electric circuit in control of the actuation of the signal-indicating means, a source of electrical energy for the controlling circuit, a thermo-electric energy-transmuter arranged to charge the source of electricity, and a common source of heat arranged to supply thermal energy both to the thermo-electric energy-transmuter and to the first mentioned thermal energy-transmuting means. 125
114. Railway signaling apparatus comprising signal-indicating means, fluid-pressure motive means in actuating co-operation therewith, a motive fluid conduit leading to the motive means, a source of motive fluid for the conduit, and a source of heat arranged to heat the motive fluid conduit. 130
115. Railway signaling apparatus comprising signal-indicating means, fluid-pressure motive means in actuating relation to the signal-indicating means, a source of motive fluid for the conduit, a controlling valve interposed in the conduit, and a source of heat arranged to heat the conduit and the motive fluid therein at a point between its controlling valve and the fluid-pressure motive means. 135
116. Railway signaling apparatus comprising signal-indicating means, fluid-pressure motive means in actuating co-operation with the signal-indicating means, a source of motive fluid, a conduit leading from such source to the motive means, a source of heat arranged to heat a portion of the motive fluid conduit, and a casing surrounding the heated portion thereof. 140
117. Railway signaling apparatus comprising signal-indicating means, a source of heat, fluid-pressure motive means in actuating co-operation with the signal-indicating means, a source of motive fluid, a motive fluid conduit leading from such source to the motive means and including one or more convolutions arranged to be heated by the source of heat. 145
118. Railway signaling apparatus comprising signal-indicating means, a source of heat, fluid-pressure motive means in actuating co-operation with the signal-indicating means, a source of motive fluid, a motive fluid conduit leading from such source to the motive means and including a heating coil arranged to be heated by the source of heat, and a casing inclosing the heating coil. 150
119. Railway signaling apparatus comprising signal-indicating means, a source of heat, fluid-pressure motive means, a source of motive fluid, a motive fluid conduit leading from such source to the motive means and including one or more convolutions arranged to be heated by the source of heat, and a controlling valve interposed in the motive fluid conduit between its source of motive fluid and its heating convolutions. 155
120. Railway signaling apparatus comprising signal-indicating means, a source of heat, a fluid-pressure motive chamber in actuating co-operation with the signal-indicating means and arranged to be heated by the source of heat, and a source of motive fluid communicating with the motive chamber. 160
121. Railway signaling apparatus comprising signal-indicating means, a source of heat, a fluid-pressure motive chamber in actuating co-operation with the signal-indicating means and arranged to be heated by the source of heat, a casing inclosing the motive chamber, and a source of motive fluid communicating with the motive chamber. 165
122. Railway signaling apparatus comprising signal-indicating means, a source of heat, a fluid-pressure motive

- chamber in actuative relation to the signal-indicating means and disposed above the source of heat and having its lower side open so that both its outer and its inner walls may be heated by the source of heat. 85
- 5 123. Railway signaling apparatus comprising signal-indicating means, a source of heat, a fluid-pressure motive chamber in actuative co-operation with the signal-indicating means and arranged to be heated by the source of heat, a source of motive fluid communicating with the motive chamber and means for controlling such communication between the source of motive fluid and the motive chamber. 90
- 10 124. Railway signaling apparatus comprising signal-indicating means, a source of heat, a fluid-pressure motive chamber in actuative co-operation with the signal-indicating means and arranged to be heated by the source of heat, a motive fluid conduit leading to the motive chamber and also arranged to be heated by the source of heat, and a source of motive fluid communicating with the motive fluid conduit. 95
- 15 20 125. Railway signaling apparatus comprising signal-indicating means, a source of heat, a fluid-pressure motive chamber in actuative co-operation with the signal-indicating means and arranged to be heated by the source of heat, a motive fluid conduit leading to the motive chamber and also arranged to be heated by the source of heat, a source of motive fluid communicating with the motive fluid conduit, and inclosing walls surrounding the motive chamber and the heated portion of the motive fluid conduit. 100
- 25 30 126. Railway signaling apparatus comprising signal-indicating means, a source of heat, a fluid-pressure motive chamber in actuative co-operation with the signal-indicating means and arranged to be heated by the source of heat, a source of motive fluid, a motive fluid conduit leading from such source to the motive chamber and including a portion arranged to be heated by the source of heat, and a controlling valve interposed in the motive fluid conduit. 105
- 35 40 127. Railway signaling apparatus comprising signal-indicating means, a source of heat, a fluid-pressure motive chamber in actuative co-operation with the signal-indicating means and arranged to be heated by the source of heat, a source of motive fluid, a motive fluid conduit leading from such source to the motive chamber and including a portion arranged to be heated by the source of heat, and a controlling valve interposed in the motive fluid conduit between its heated portion and its source of motive fluid. 110
- 45 50 128. Railway signaling apparatus comprising signal-indicating means located at a plurality of signaling points in proximity to a railway line, one or more controlling electric circuits in control of the signal-indicating means, at a given one of the signaling points fluid-pressure motive apparatus in actuative relation to the signal-indicating means at such given point, a source of motive fluid communicating with the fluid-pressure motive means through suitable pressure-reducing means, at the given signaling point thermo-electric energy-transmuting means arranged to supply energy to one of the signaling circuits, and also at such given signaling point a common source of heat arranged both to heat the fluid-pressure motive apparatus and to supply thermal energy-transmuter. 115
- 55 60 129. Railway signaling apparatus comprising signal-indicating means located at a plurality of signaling points in proximity to a railway line, one or more controlling electric circuits in control of the signal-indicating means, at a given one of the signaling points fluid-pressure motive apparatus in actuative relation to the signal-indicating means at such point, a motive fluid reservoir communicating with the fluid-pressure motive apparatus, a source of motive fluid communicating with the reservoir through suitable pressure-reducing means, at the given signaling point a thermo-electric energy-transmuting means arranged to supply energy to one of the signaling circuits, and also at the given signaling point a common source of heat arranged both to heat the fluid-pressure motive apparatus and to supply thermal energy to the thermo-electric energy-transmuter. 120
- 65 70 75 130. Railway signaling apparatus comprising signal-indicating means, a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive fluid after it has passed from the reservoir. 125
- 80 131. Railway signaling apparatus comprising signal-indicating means, a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive fluid conduit. 130
- 85 132. Railway signaling apparatus comprising signal-indicating means, a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive chamber. 135
- 90 133. Railway signaling apparatus comprising signal-indicating means, a fluid-pressure motive chamber, a source of motive fluid, a reservoir for motive fluid communicating with the source of motive fluid through suitable pressure-reducing means, a motive fluid conduit leading from the reservoir to the motive chamber, and a source of heat arranged to heat the motive fluid conduit and the motive chamber. 140
- 95 134. Railway signaling apparatus comprising signal-indicating means, a fluid-pressure motive chamber in actuative relation thereto, a source of motive fluid, a motive fluid reservoir communicating with the source of motive fluid through suitable pressure-reducing means, a motive fluid conduit leading from the motive fluid reservoir to the fluid-pressure motive chamber, a controlling valve interposed in the motive fluid conduit, and a source of heat arranged to heat the motive fluid after it has passed through the controlling valve. 145
- 100 135. Railway signaling apparatus comprising signal-indicating means located at a plurality of signaling points in proximity to a railway line, one or more controlling electric circuits in control of the signal-indicating means, at a given one of the signaling points a fluid-pressure motive apparatus in actuative co-operation with the signal-indicating means and also at such given point a thermo-electric energy-transmuting means arranged to supply energy to one of the controlling circuits, and also at the given signaling point a source of heat arranged both to heat the motive fluid of the fluid-pressure motive apparatus and to supply thermal energy to the thermo-electric energy-transmuter. 150
- 105 136. Railway signaling apparatus comprising signal-indicating means located at a plurality of signaling points in proximity to a railway line, signaling circuits in control of the signal-indicating means, at a given one of the signaling points fluid-pressure motive apparatus in actuative co-operation with the signal-indicating means at such point, and also at the given signaling point a thermo-electric energy-transmuting apparatus including a source of thermal energy and arranged to deliver its surplus or non-utilized heat to the fluid-pressure motive apparatus to warm the motive fluid thereof and arranged to deliver its energy to one of the signaling circuits. 155
- 110 137. Railway traffic-controlling apparatus comprising traffic-controlling means located at a fixed traffic-controlling point on a railway track and arranged in control of traffic along the track, and fluid-pressure motive apparatus in actuative co-operation with the traffic-controlling means and including a source of motive fluid, a motive chamber communicating therewith and arranged to convert the expansive energy of the motive fluid into mechanical energy for actuating the traffic-controlling means, and a source of heat arranged to heat the motive fluid of the motive apparatus. 160
- 115 138. Railway traffic-controlling apparatus comprising traffic-controlling means located at a fixed traffic-controlling point on a railway track and arranged in control of traffic along the track, and fluid-pressure motive apparatus including a source of motive fluid, a motive expansion chamber communicating with the source of motive fluid and in actuative relation to the traffic-controlling means, means for controlling communication between the source of motive fluid and the motive expansion chamber, and a 160

- source of heat arranged to heat the motive fluid of the motive apparatus.
139. Railway traffic-controlling apparatus comprising traffic-controlling means located at a fixed traffic-controlling point on a railway track and arranged in control of traffic along the track, and fluid-pressure motive apparatus including a source of pressure fluid, a pressure-fluid reservoir communicating with the source of pressure fluid through suitable pressure-reducing means, a motive chamber communicating with the pressure-fluid reservoir and arranged in actuating relation to the traffic-controlling means, and a source of heat arranged to heat the pressure fluid of the motive apparatus.
140. Railway traffic-controlling apparatus comprising traffic-controlling means located at a fixed traffic-controlling point on a railway track and arranged in control of traffic along the track, and fluid-pressure motive apparatus including a source of pressure fluid, a pressure-fluid reservoir communicating with the source of pressure fluid through suitable pressure-reducing means, a motive chamber communicating with the pressure-fluid reservoir and arranged in actuating relation to the traffic-controlling means, and a source of heat arranged to heat the pressure fluid of the motive apparatus.
141. Railway signaling apparatus comprising signal-indicating means and fluid-pressure motive apparatus in actuating co-organization with the signal-indicating means and including a source of motive fluid, a motive chamber communicating therewith and arranged to convert the expansive energy of the motive fluid into mechanical energy for actuating the signal-indicating means, and a source of heat arranged to heat the motive fluid of the motive apparatus.
142. Railway signaling apparatus comprising signal-indicating means and fluid-pressure motive apparatus including a source of motive fluid, a motive expansion chamber communicating with the source of motive fluid and in actuating relation to the signal-indicating means, means for controlling communication between the source of motive fluid and the motive expansion chamber, and a source of heat arranged to heat the motive fluid of the motive apparatus.
143. Railway signaling apparatus comprising signal-indicating means and fluid-pressure motive apparatus including a source of pressure fluid, a pressure-fluid reservoir communicating with the source of pressure fluid through suitable pressure-reducing means, a motive chamber communicating with the pressure-fluid reservoir and arranged in actuating relation to the signal-indicating means, and a source of heat arranged to heat the pressure fluid of the motive apparatus.
144. Railway signaling apparatus comprising signal-indicating means and fluid-pressure motive apparatus including a source of pressure fluid, a pressure-fluid reservoir communicating with the source of pressure fluid through suitable pressure reducing means, a motive chamber communicating with the pressure-fluid reservoir and arranged in actuating relation to the signal-indicating means, and a source of heat arranged to heat the pressure fluid of the motive apparatus.

In testimony whereof I affix my signature in presence of two witnesses.

CLYDE J. COLEMAN.
